CLAIM

The ornamental designs for sockets for relays, as shown and described.

DESCRIPTION

FIG. 1 is a perspective view of the top, front and left side of a socket;

FIG. 2 is a top plan view of the socket;

FIG. 3 is a bottom plan view of the socket;

FIG. 4 is a front view of the socket;

FIG. 5 is a back view of the socket;

FIG. 6 is a right side view of the socket; and,

FIG. 7 is a left side view of the socket.

The broken line portion of the figure drawings is included to show unclaimed subject matter only and forms no part of the claimed design.
